(57) **CLAIM**

The ornamental design for a vehicle latch, as shown and described.

DESCRIPTION

FIG. 1 is a top perspective view of a vehicle latch showing our new design;

FIG. 2 is a bottom perspective view of the vehicle latch of FIG. 1;

FIG. 3 is a front side view of the vehicle latch of FIG. 1;

FIG. 4 is a rear side view of the vehicle latch of FIG. 1;

FIG. 5 is a top view of the vehicle latch of FIG. 1;

FIG. 6 is a bottom view of the vehicle latch of FIG. 1;

FIG. 7 is a right side view of the vehicle latch of FIG. 1; and,

FIG. 8 is a left side view of a vehicle latch of FIG. 1 showing our new design.

The broken lines in the drawings depict portions of the vehicle latch that form no part of the claimed design.

1 Claim, 4 Drawing Sheets
